MECHANICAL APPARATUS TO INJECT
FLUIDS INTO WELLS IN BATCHES

James A. Clay, Jr., Fort Worth, Tex.

Application October 26, 1948, Serial No. 56,506

3 Claims. (Cl. 222—442)

1

This invention relates to apparatus for feeding chemicals or other fluids into oil, gas or water wells, and more particularly to an apparatus whereby an oil, gas or water well may be treated with a chemical solution or fluid in batches, the batches being supplied periodically to the well under treatment.

There are many conditions affecting wells that require the use of small amounts of chemicals daily. Wells may be subject to paraffin accumulations which require solvents for their removal; wells may be subject to scaling conditions such as accumulations and deposits of carbonates, sulphates, and the like, which require daily injection of chemicals to control. Many wells are subject to corrosion of subsurface equipment and said corrosion may be mitigated through the use of chemical inhibitors injected daily; and some well fluids are produced in an emulsified form and the emulsions produced may be broken through the use of chemical compounds injected daily.

The methods heretofore used to accomplish the above have depended upon one of two types of systems: (1) A chemical injecting apparatus which is capable of injecting up to five (5) gallons a day, but which does so substantially a drop at a time. This method has proven unsatisfactory many times because of the fact that insufficient fluid is injected at any one moment to allow it to reach the bottom of the well. The fluid injected clings to the walls of the subsurface equipment and therefore does not reach the bottom of the well. (2) An apparatus to inject fluids into wells in batches which, however, requires the attendance of one or more persons to manually manipulate the apparatus. This introduces the human element, and such apparatus has been proven unsatisfactory.

A prime purpose of the present invention is to provide an apparatus which will mechanically and automatically treat wells with fluids or chemicals in batches without depending upon a person or persons for daily attendance.

Another object of the invention is to provide a novel and improved apparatus for delivering substantial charges of chemical solution or other fluid at periodic intervals to an oil well, gas well, water well, or the like, said apparatus being very simple in construction, reliable in operation, and being driven from the well pumping beam or other moving portion of the well pump mechanism.

A further object of the invention is to provide an improved automatic apparatus for injecting

2

batches of chemical solution or the like at periodic intervals into an oil, gas or water well, said apparatus being easy to install, being rugged in construction, and furnishing accurately metered charges of material in substantial volume at the desired regular intervals to the well being treated.

Further objects and advantages of the invention will become apparent from the following description and claims, and from the accompanying drawings, wherein:

Figure 1 is a side elevational view of a portion of the pumping mechanism of an oil well, equipped with a mechanism for periodically furnishing batches of fluid to the well constructed in accordance with the present invention.

Figure 2 is a fragmentary top plan schematic view of the batch injecting mechanism employed in the apparatus of Figure 1.

Figure 3 is an enlarged top plan view of the batch injecting mechanism with the top cover of the cam box removed.

Figure 4 is an enlarged cross-sectional detail view taken on line 4—4 of Figure 3.

Figure 5 is a cross-sectional detail view taken on line 5—5 of Figure 3.

Figure 6 is a cross-sectional view taken on line 6—6 of Figure 3.

Figure 7 is an enlarged cross-sectional detail view taken on line 7—7 of Figure 3.

Referring to the drawings, 11 designates a well provided with a conventional pumping apparatus 12 which includes an oscillating walking beam 13 pivoted to the top portion of a fulcrum tower 14. Designated at 15 is a storage tank containing the fluid to be injected into the well. Tank 15 is supported at a substantial elevation on a suitable stand or frame 16.

Designated at 17 is a housing supported on the ground adjacent frame 16. Mounted on the top of housing 17 is a metering tank 18, said tank 18 being below the level of the storage tank 15. Extending from the bottom portion of metering tank 18 is a first conduit 19 which leads to the well bore 11, said conduit 19 passing through housing 17. Conduit 19 is provided with a first valve 20 in housing 17 and a manual valve 21 located between valve 20 and well 11 externally of housing 17.

Extending from the bottom portion of storage tank 15 to conduit 19 ahead of valve 20 is a second conduit 22 which is provided inside of housing 17 with a second valve 23 similar to valve 20. Connected to the upper portion of tank 18 and extending through housing 17 is a third or vent conduit 24 which communicates with the atmos-

phere and is provided with a third valve 25 also similar to valve 20. Connecting the upper portion of storage tank 15 to conduit 24 ahead of valve 25 is a fourth conduit 26 provided with a fourth valve 27 also similar to valve 20. The end of vent pipe 24 is open to atmosphere.

As above stated, the valves 20, 23, 25 and 27 are similar in construction. Each valve comprises a body 28 having a partition 29 dividing said body into two chambers. Partition 29 is apertured at 30 to define a valve opening and seated on the partition in covering relation to said opening is a valve disc 31 carried by a vertically movable valve rod 32 slidably supported for vertical movement in the upper portion of valve body 28. Valve body 28 is formed with a yoke portion 33 through which valve rod 32 slidably passes, said rod having secured thereto a collar 34. Encircling rod 32 is a coiled spring 35 which bears between yoke 33 and collar 34, biasing rod 32 downwardly whereby valve disc 31 is urged to a seated position on partition 29, closing off the opening 30, as shown in Figure 7. Each valve rod 32 is formed at its top end with a head 36.

Housing 17 is divided by a partition wall 37 into two compartments indicated respectively at 38 and 39, the valves 23, 20, 27 and 25 being located in compartment 38. Secured transversely in compartment 38 is a shaft 40, and rotatably secured to said shaft are the respective valve levers 41, 42, 43 and 44. The right ends of the levers, as viewed in Figures 3 and 4, are formed with apertures 45 receiving the respective valve rods 32 of the valves 23, 20, 27 and 25, the heads 36 of said rods bearing on the upper surfaces of said levers, whereby counterclockwise rotation of the levers, as viewed in Figure 4, raises the valve rods and opens the valves. The springs 35 normally maintain the valves in closed positions.

Designated at 46 is a shaft journaled transversely in housing 17 and extending through both compartments 38 and 39, overlying the left ends of the levers 41, 42, 43 and 44, as viewed in Figures 3 and 4. Shaft 46 carries the respective first, second, third, fourth cams 47, 48, 49 and 50 overlying the ends of the respective levers 41, 42, 43 and 44. In compartment 39 shaft 46 carries a worm gear 51. Journaled vertically in compartment 39 is a shaft 52 carrying a worm 53 meshing with worm gear 51, and also carrying a worm gear 54. Journaled transversely in compartment 39 is a shaft 55 carrying a worm 56 meshing with worm gear 54, and also carrying a ratchet wheel 57. Rotatably mounted in the rear wall of compartment 39 and rotatably receiving shaft 55 is a sleeve member 58 provided with a resilient pawl arm 59 which engages the toothed periphery of wheel 57. Sleeve 58 is also provided with an external rigid arm 60 which is connected by a link rod 61 to walking beam 13. Oscillation of said walking beam is transmitted by rod 61 and arm 60 through sleeve 58 to pawl arm 59, causing ratchet wheel 57 to be rotated clockwise, as viewed in Figure 5, each time walking beam 13 oscillates counterclockwise, as viewed in Figure 1. Pivottally secured to the rear wall of compartment 39 is a depending ratchet dog 62 engaging the toothed periphery of wheel 57 to prevent said wheel from rotating counterclockwise, as viewed in Figure 6.

The intermittent clockwise rotation of wheel 57, as viewed in Figure 5, is transmitted through shaft 55 to worm 56, causing worm gear 54 and worm 53 to be rotated counterclockwise, as viewed in Figure 3. This rotates gear 51 coun-

terclockwise, as viewed in Figure 5, causing shaft 46 to be similarly rotated. Said shaft therefore is rotated at a substantial reduction in speed as compared with the rate of oscillation of walking beam 13.

Referring to Figures 3 and 4, it will be seen that the eccentric cams 47, 48, 49 and 50 are related in phase as follows: Cams 47 and 49 are identical in phase and engage the levers 41 and 43 simultaneously to produce simultaneous opening and closing of the valves 23 and 27. Cam 48 lags behind cams 47 and 49 by a substantial angle, whereby it engages lever 42 after valves 23 and 27 are closed, to thereby produce opening and closing of the valve 20. Cam 50 lags behind cam 48 by a substantial angle, whereby it engages lever 44 after valve 20 has closed thereby opening and closing the valve 25. Therefore, as shaft 46 rotates, the following sequence of operations occurs:

1. Valves 23 and 27 open. Fluid flows from storage tank 15 through conduits 22 and 19 into metering tank 18. Gas displaced from the upper portion of metering tank 18 flows through conduits 24 and 26 into the upper portion of tank 15, permitting the fluid to fill the metering tank.

2. Valves 23 and 27 close.

3. Valve 20 opens and drains fluid from metering tank 18 through conduit 19 into the well head opening 11, the manual valve 21 having been previously set in open position.

4. Valve 20 closes.

5. Valve 25 opens and blows off to atmosphere through vent conduit 24 any gases that may have passed from the well into the metering tank 18 while valve 20 was open.

6. Valve 25 closes.

7. The above operation repeats itself at periodic intervals determined by the rate of oscillation of walking beam 13 and the speed reduction ratio provided by the above described mechanism.

Tank 18 is preferably provided at its top wall with an air intake check valve 63 to prevent a vacuum from forming in the upper portion of the metering tank while the fluid is draining from said tank into the well head opening.

While a specific embodiment of an apparatus for feeding chemicals or other fluids into oil, gas, or water wells in periodic batches of substantial volume has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A liquid feeding apparatus comprising an upstanding support, a storage tank mounted upon said support, a metering tank arranged below said storage tank, a first conduit having one end connected to the lower portion of said metering tank and having the other end adapted for connection to a confined space, a second conduit having one end connected to the lower portion of said storage tank and having the other end connected to said first conduit adjacent said one end thereof, a third conduit having one end connected to the upper portion of said metering tank and having the other end adapted to communicate with the atmosphere, a fourth conduit having one end connected to the upper portion of said storage tank and having the other end connected to said third conduit intermediate the

ends of the latter, a first openable and closable valve in said first conduit intermediate the ends thereof, a second openable and closable valve in said second conduit intermediate the ends thereof and positioned in aligned lateral relation with respect to said first valve, a third openable and closable valve in said third conduit intermediate the ends thereof and positioned in aligned lateral relation with respect to said second valve, a fourth openable and closable valve in said fourth conduit intermediate the ends thereof and positioned in aligned lateral relation with respect to said third valve, a rotatable shaft, first, second, third and fourth cams arranged in spaced relation along and carried by said shaft, said first and third cams being identical in phase and being connected respectively to said second and fourth valves to simultaneously open and close in sequence the latter valves, said second cam being of a different phase than said first and third cams and being connected to said first valve to open and close in sequence the latter valve after the sequential opening and closing of said second and fourth valves, said fourth cam being of a different phase than said second cam and that of said first and third cams and being connected to said third valve to open and close in sequence the latter valve after the sequential opening and closing of said first valve.

2. A liquid feeding apparatus comprising an upstanding support, a storage tank mounted upon said support, a metering tank arranged below said storage tank, a first conduit having one end connected to the lower portion of said metering tank and having the other end adapted for connection to a confined space, a second conduit having one end connected to the lower portion of said storage tank and having the other end connected to said first conduit adjacent said one end thereof, a third conduit having one end connected to the upper portion of said metering tank and having the other end adapted to communicate with the atmosphere, a fourth conduit having one end connected to the upper portion of said storage tank and having the other end connected to said third conduit intermediate the ends of the latter, a first openable and closable valve in said first conduit intermediate the ends thereof, a second openable and closable valve in said second conduit intermediate the ends thereof and positioned in aligned lateral relation with respect to said first valve, a third openable and closable valve in said third conduit intermediate the ends thereof and positioned in aligned lateral relation with respect to said second valve, a fourth openable and closable valve in said fourth conduit intermediate the ends thereof and positioned in aligned lateral relation with respect to said third valve, a rotatable shaft, first, second, third and fourth cams arranged in spaced relation along and carried by said shaft, said first and third cams being identical in phase and being connected respectively to said second and fourth valves to simultaneously open and close in sequence the latter valves, said second cam being of a different phase than said first and third cams and being connected to said first valve to open and close in sequence the latter valve after the sequential opening and closing of said second and fourth valves, said fourth cam being of a different phase

than said second cam and that of said first and third cams and being connected to said third valve to open and close in sequence the latter valve after the sequential opening and closing of said first valve, and means operatively connected to said shaft for producing the rotation of the latter to effect in sequence the opening and closing movements of the respective valves.

3. A liquid feeding apparatus comprising an
10 upstanding support, a storage tank mounted
upon said support, a metering tank arranged
below said storage tank, a first conduit having
one end connected to the lower portion of said
15 metering tank and having the other end adapt-
ed for connection to a confined space, a second
conduit having one end connected to the lower
portion of said storage tank and having the
other end connected to said first conduit adjac-
20 ent said one end thereof, a third conduit hav-
ing one end connected to the upper portion of
said metering tank and having the other end
adapted to communicate with the atmosphere,
a fourth conduit having one end connected to
25 the upper portion of said storage tank and hav-
ing the other end connected to said third conduit
intermediate the ends of the latter, a first
30 openable and closable valve in said first conduit
intermediate the ends thereof, a second open-
able and closable valve in said second conduit
intermediate the ends thereof and positioned in
aligned lateral relation with respect to said first
35 valve, a third openable and closable valve in
said third conduit intermediate the ends thereof
and positioned in aligned lateral relation with
respect to said second valve, a fourth openable
and closable valve in said fourth conduit inter-
40 mediate the ends thereof and positioned in
aligned lateral relation with respect to said third
valve, a rotatable shaft, first, second, third and
fourth cams arranged in spaced relation along
and carried by said shaft, said first and third
45 cams being identical in phase and being con-
nected respectively to said second and fourth
valves to simultaneously open and close in se-
quence the latter valves, said second cam being
of a different phase than said first and third
50 cams and being connected to said first valve to
open and close in sequence the latter valve after
the sequential opening and closing of said sec-
ond and fourth valves, said fourth cam being
of a different phase than said second cam and
55 that of said first and third cams and being con-
nected to said third valve to open and close in
sequence the latter valve after the sequential
opening and closing of said first valve, and an
oscillating means operatively connected to said
60 shaft for producing the rotation of the latter to
effect in sequence the opening and closing move-
ments of the respective valves.

JAMES A. CLAY, JR.
